UNITED STATES PATENT OFFICE.

MAURICE FRANK HUTCHISON, OF HERNDON, VIRGINIA.

AUTOMATIC DRAFT-REGULATOR AND RETURN-TRAP.

1,261,030.

Specification of Letters Patent. Patented Apr. 2, 1918.

Application filed August 24, 1917. Serial No. 187,919.

To all whom it may concern:

Be it known that I, MAURICE FRANK HUTCHISON, a citizen of the United States, residing at Herndon, county of Fairfax, 5 and State of Virginia, have invented certain new and useful Improvements in Automatic Draft-Regulators and Return-Traps, of which the following is a full, clear, and exact specification.

10 This invention relates to draft regulators automatically controlled by the heating plants to which they are attached and is especially designed for vapor heating systems.

15 The invention also includes an improved safety appliance for relieving excess pressure in emergencies.

One object of the invention is to prevent 20 the water or steam backing up from the boiler into the radiators in case of excessive pressure of vapor in the boiler due, for instance, to the ash pit door being left open.

Another object is to utilize the water of condensation from the radiators for operating 25 the damper regulator.

A further object is to dispense with all 30 check, thermostatic and float valves heretofore used in vapor heating systems and provide a device which has no movable parts in the returns from the radiators to the boiler.

Still another object is to provide means 35 for adjusting the regulator so that it will automatically operate the dampers at different predetermined pressures of the vapor in the system.

The invention will be first hereinafter described in connection with the accompanying drawings, which constitute a part of this specification, and then more specifically defined in the claims at the end of the description.

In the accompanying drawings, wherein 40 similar reference characters are used to designate corresponding parts in all the views:

Figure 1 is a side elevation of the boiler of a vapor heating plant, showing my improved damper regulator attached;

Fig. 2 is a front elevation of the same; 50 Fig. 3 is an enlarged detail sectional view of the trap receiver;

Fig. 4 is an enlarged front elevation of

the adjusting means for varying the pressure required to operate the dampers;

Fig. 5 is a diagrammatic view illustrating 55 the arrangement of the system, and

Fig. 6 is an enlarged detail sectional view of a modified form of trap.

The normal water line in the boiler A is indicated by a broken line $a-a$ in Fig. 1, 60 and said line is extended across the trap receiver B which is connected to the return inlet of the boiler by a pipe C.

This pipe fits into a bored boss D extending upwardly from the bottom of the trap receiver (see 65 Fig. 3). Obviously the water line in the pipe C or in the boss D, which is in effect a continuation of the pipe C, will be on the same level as the water line in the boiler.

As a general proposition the water line in 70 the boiler normally is at or just below the top of said boss D. As shown in Figs. 1 to 5 the main portion of the trap receiver surrounding the boss D is connected to the radiators of the heating plant by the return 75 pipe E entering the bottom of said trap receiver.

The looped portion of said pipe E below the trap receiver constitutes the trap proper. However, it is not intended to limit this invention to this particular form 80 of trap as any trap, broadly speaking, may be utilized. A modified form of trap is shown in Fig. 6, wherein the downwardly extending portion of return pipe E below said trap receiver D is dispensed with and 85 the upwardly extending portion of said return pipe E^x, Fig. 6, opens directly into the trap receiver B and extends to a point below the upper edge of the boss D^x.

Equally as good results are obtained by this 90 form of trap as the trap arrangement shown in the other figures. The feed pipe F from the boiler to the radiators has a branch pipe F' leading to the top of the trap receiver.

From a point in the pipe E a branch pipe 95 G leads to a hollow globe or reservoir H, there being a flexible section G' in said pipe.

The globe H normally stands above the water level in the trap receiver B, as seen in Fig. 1. An air vent pipe or tube J, preferably flexible, leads from the top of said globe or reservoir to the pipe E at a point 100 above said water level in the trap receiver B. Said pipe E is also provided with a

vent branch E' arranged at a still higher level. Said vent pipe E' rises from a horizontal portion of the return pipe E, so that the proper return of the water of condensation is not affected, but in case the water backs up in said return pipe, as hereinafter explained, due to excessive pressure of the vapor on said water, said water in the vertical portion of the return pipe E and trap receiver B will be forced into the horizontal portions E² of the return pipes and when all of said water has been forced into said horizontal portions of the return pipes E, the vapor following will escape through the vent pipe E', the water in the horizontal portions of said return pipe returning automatically and re-sealing the trap after the pressure falls, as will be obvious. The amount of water contained in the vertical portion of the return pipe E and trap receiver B is not sufficient to cause said water to reach the radiators and back up therein, but such water simply remains or lies in the horizontal portions of the return pipe E until the pressure falls, and as stated, then returns automatically to re-seal the trap.

The reservoir H is adjustably connected to an intermediate part of a chain or other flexible connection K secured at one end to a direct draft damper L in the ash door, and at the other end to a check damper M in the flue N leading from the boiler to the chimney. This chain K is passed over sheaves P so that when moved in one direction it opens one damper and closes the other, and vice versa.

In operation, when the vapor or steam pressure rises above a predetermined point, water is forced up into the reservoir H. The trap receiver B and pipe E contain sufficient water to fill said reservoir H and to maintain a predetermined pressure in the boiler. As soon as said reservoir starts to fill, the added weight of the water therein causes it to gradually lower or drop, overcoming the spring R which normally acts as a counterbalance for said reservoir and the parts attached thereto. By reason of the connection between said reservoir and chain K, when the reservoir drops the direct draft damper L is closed and the check draft damper M opened, retarding combustion and obviously causing the pressure of vapor to be reduced. When such pressure has become reduced to the desired degree the water will run back from the reservoir H, whereupon the spring R will raise said reservoir to the position shown in the drawings, thereby opening the direct draft damper again and closing the check draft damper.

It will be noted that the water which enters the reservoir and serves to operate the dampers is taken from the return pipe E from the radiators and which is connected

to the bottom of the portion of the trap receiver B surrounding the boss D. It is therefore, the water of condensation from the radiators that is used for this purpose. The pressure in the boiler is communicated to the trap receiver B by the branch pipe F' and acts upon the surface of the water of condensation in said trap receiver to force the same into the reservoir H, and at the same time equalizes the pressure on the water in pipe C. The water of condensation is, of course, generally overflowing the boss D in the trap receiver and serves to replenish the boiler from which the water is constantly being converted into vapor.

The vent pipe E' in conjunction with the vent pipe J prevents the formation of a vacuum in the reservoir when the water flows from the same back into the trap via the pipes G, G'. The vent pipe E', in conjunction with the trap also serves as a safety device, allowing the water in the vertical portion of the return pipe E and the trap receiver B to be forced past said vent pipe into horizontal portions of the return pipe E and the vapor following to escape through the vent pipe in case the pressure in the boiler becomes too high, which might occur if the ash pit door was left open and the ordinary safety valve failed to operate. In such an emergency the water in the trap and in the vertical portions of the return pipe E would be forced into the horizontal portions of the return pipe E by the pressure of vapor entering the trap through pipe F' without affecting the water in the boiler to any appreciable extent inasmuch as the pressure on the surfaces of the water in the boiler and on the surface of the water in the boss D or pipe C is the same. The vapor following the water thus forced into the horizontal portions of the return pipe then escapes through vent pipe E' to the atmosphere. As will be apparent from the diagrammatic view part of the water thus forced into the horizontal portions of the return pipes is forced into the horizontal portion to the left of the upwardly extending portion of the return pipe E and part of the water forced into the horizontal portion of the return pipe E beyond the connection of the vent pipe E' with said horizontal portion E² and to a point in said horizontal portion of said pipe between the vent pipe connection therewith and the radiators. Should all the water in the trap and return pipe E be forced out in this way, the vapor will follow and relieve the pressure in the boiler in an obvious manner. It will be observed that if it were not for the vent pipe E', excessive pressure in the boiler, under the conditions mentioned, would cause the water in the trap and return pipe E to back up in said return pipe and radiators. The return pipes it will be understood are of suf-
